UNITED STATES PATENT OFFICE

ALBERT C. DENMARK AND LOUIS O. BRYANT, OF AUSTIN, TEXAS

KITCHEN UTENSIL

Application filed June 1, 1928. Serial No. 282,167.

Our present invention has reference to a combination tool, particularly adaptable for use in a kitchen, and the primary object of the invention is to provide a relatively simple, strong and durable tool in which is combined a number of tools and devices that are frequently required for use about a household or kitchen.

With the foregoing and other objects in view the invention consists in the novel features of construction, combination and operative association of parts, that will be herein-after more fully described and claimed and illustrated in the accompanying drawings

and in which:

Figure 1 is a side elevation of our improvement with parts in section.

Figure 2 is a top plan view thereof.

Figure 3 is a bottom plan view thereof.

20 In constructing our improved tool we make use of a pair of handles 1 and 2, respectively, the said handles having their outer faces round in cross section and their inner faces flat. The outer end of the handle 1 is flattened and constructed to provide a bifurcated claw member 3 which may be employed as a tack puller. The outer end of the handle 2 is likewise flattened and rounded, but is not bifurcated, and this portion, indicated by the

30 numeral 4, may be employed for prying the lids off of cans, lifting stove lids and the like. The handles 1 and 2 have their opposite ends directed toward each other, and these portions are flattened and have upon their opposite sides substantially rounded depressions and rounded portions to be received in the depressions, the said rounded portions being pivotally connected, as at 5. From the pivot the handle 2 is extended and bent down-

40 wardly to provide a flattened jaw 6, the rounded or extended portion above the jaw being formed with an outwardly directed pointed lug 7. The portion of the handle 1, beyond its pivot is bent in an opposite direction from that of the part of the handle 2 provided with the pointed lug and from

45 thence extended angularly toward the jaw 6, as at 8 and merges into a straight jaw 9 that is disposed opposite the jaw 6. The jaws 6 and 9 provide the device with a pan lifter

whereby heated utensils may be raised from a stove and conveyed without liability of inflicting injury to the hand of the user. Inward of its downward extension that merges into the part 8 the handle 2 is formed with an outwardly directed hook 10 that affords a bottle opener. To the rear of the hook 10, the outer face of the handle 2 is provided with a pocket 11 in which is pivoted one end of a cork screw 12. The inner flat face of the handle 2 is provided with a round opening or socket 13, and the jaw 1 is formed with a pin or post 14 which extends from its inner flat face and which is designed to be received in the socket 13. The purpose of this arrangement will be presently described.

Slidable on the handle 1, between the pin or post 14 and the pivot 5 there is a sleeve 15 that has on its outer end two spaced cutter elements 16 and 17, respectively. The post 14 limits the movement of the sleeve in the direction thereof and the cutting elements, together with the pointed element 7 provide the device with a can opener. By forming the sleeve 15 with two spaced cutting elements, one of the said elements may serve as a guide for the other and likewise one of these elements may be employed when the other becomes dull or broken.

The pin or post 14 holds the handles and the jaws in proper alignment and prevents any tendency of lateral movement of the handles and also, in connection with the socket 13, provides the improvement with a punch. In addition to this the member 14 serves as a stop for limiting the sliding movement of the sleeve 15 in one direction, the movement of the sleeve in a second direction being limited by the contact therewith of the rounded and pivoted portion of the handle 1.

A combination tool of our improved construction is relatively simple and may be easily and cheaply produced, is very compact, and combines in a single construction a number of tools and devices that are generally useful about a household, or kitchen.

Having described the invention, we claim:

1. A tool comprising a pair of handles, a flattened portion formed on one end of each of the handles, means pivotally connecting

said flattened portions in overlapping relation to each other and one of said portions extending into a plane above the handles, a pointed and hook-shaped member formed on the upper edge of said last named flattened portion and extending upwardly and outwardly of the handles, a cutting element slideable on one of the handles to cooperate with the hook-shaped member in forming a can 10 opener, and means to maintain the handles in fixed relation while in operation as a can opener.

2. A tool comprising a pair of handles, overlapping flat portions formed on the handles and pivotally connected together, one of said flattened portions extending into a plane above the handles, a penetrating hook carried by the last mentioned flattened portion and extending upwardly and forwardly of 15 the handles, a sleeve slidably mounted on one of the handles and adapted to be limited in one direction by the flattened portions and in the other direction by said handle connecting means, cutting elements carried by 20 the upper portion of the sleeve and adapted to cooperate with the hook in forming a can opener, and means to maintain the handles in fixed relation while in operation as a can opener.

30 In testimony whereof we affix our signatures.

**ALBERT C. DENMARK.
LOUIS O. BRYANT.**
